[57] CLAIM

The ornamental design for a shoe heel and counter protector, as shown and described.

DESCRIPTION

FIG. 1 is a perspective view of a shoe heel and counter protector showing our new design;

FIG. 2 is a rear elevational view thereof;

FIG. 3 is a side elevational view thereof, the opposite side being a mirror image thereof;

FIG. 4 is a front elevational view thereof;

FIG. 5 is a top view thereof; and

FIG. 6 is a bottom view thereof.
